UNITED STATES PATENT OFFICE

2,202,796

COVER FOR TOBACCO JARS

Louis Hermani, Baltimore, Md., assignor to
 Owens-Illinois Can Company, a corporation of
 Delaware

Application July 30, 1938, Serial No. 222,235

2 Claims. (Cl. 299—24)

The present invention relates to covers for tobacco jars and more particularly to a loose cover for an hermetically sealed cylindrical metallic box, the cover being of the type having a radial sliding cutter designed when the cover is pressed upon the top of the box to puncture the top, and upon rotation of the loose cover to cut out the top of the box.

It is an object of the invention to provide a tobacco jar cover of the type set forth above which is formed with a hollow enlargement thereon that serves the two-fold purpose of providing a handle by means of which the cover may be rotated to actuate the cutter and also of providing a humidifying chamber adapted to contain a moistening agent for the contents of the jar after the top thereof has been removed and the jar is employed as a humidor.

Another object of the invention is to provide such a tobacco jar cover having associated therewith a removable register of the rotary cut-off type which is frictionally and removably received within the hollow enlargement and which serves to retain the moistening agent within the latter.

Other objects of the invention, not at present enumerated, will become apparent hereinafter.

In the accompanying drawing:

Fig. 1 is a vertical sectional view taken through a tobacco jar cover manufactured in accordance with the principles of the present invention.

Fig. 2 is a bottom plan view of the cover.

Fig. 3 is a sectional view taken substantially along the line 3—3 of Fig. 2.

Fig. 4 is a plan view of a rotary cut-off disk forming one part of a register employed in connection with the present invention.

Fig. 5 is a side elevational view of the cut-off device.

Fig. 6 is a side elevational view of the stationary part of the register, and

Fig. 7 is a bottom plan view of the disclosure of Fig. 6.

The tobacco jar cover is shown in Fig. 1 applied to a tobacco jar 10, the latter being shown in dotted lines. The cover includes a circular top 11 having a peripheral strengthening rib 12 formed thereon and a depending peripheral skirt 13 adapted to be telescoped over the neck portion of the jar 10. The top 11 is provided with

a raised central portion 14 the medial part of which is cut away to provide an inwardly extending circular rim 15. A deep drawn hollow cup-shaped enlargement 16 is formed with a dome-like top 17 and a depending skirt 18 the lower edge of which is flanged outwardly over

the rim 15. The skirt wall is generally cylindrical but is flared outwardly near the top thereof as at 19 for a purpose to be set forth hereinafter.

The top 11 is provided with a short radially extending slot 25 near the periphery thereof in which there is slidably disposed a cutter 26 having a depending blade 27 designed to puncture the top of the jar 10 when the cover is pressed downwardly thereon. The enlargement 16 serves as a handle by means of which the cover may be turned upon the jar to cause the cutter blade 27 to circumscribe the top of the jar and sever the same from the neck portion thereof.

A register of the rotary cut-off type and including a stationary part 30 (Figs. 3, 6 and 7) and a rotary disk 31 (Figs. 3, 4 and 5) which is riveted thereto is telescopically disposed in the hollow enlargement 16 and is frictionally held therein by means of axially extending resilient fingers 32 formed on the stationary part 30. The fingers 32 are flared slightly outwardly as at 33 adjacent their outer ends and these flared portions 33 are received in the annular void created by the flared portion 19 of the enlargement 16. Thus it will be seen that the register is frictionally held in position in the enlargement against dislodgment.

The disk 31 is provided with a raised finger knob 34 whereby the disk may conveniently be turned relative to the stationary part 30 to bring a series of ports 35 formed in the former into register with a similar series of ports 36 formed in the latter and thereby obtain a greater or less degree of circulation of moisture down and into the jar 10. Such regulation, of course, is accomplished by removal of the cover from the jar.

The enlargement 16 provides a chamber which is adapted to contain a moistening device such as a sponge 37 or other absorbent material which may conveniently be installed therein by removal of the register and insertion of the material in the register between the fingers 32 after which the register may be replaced in the enlargement 16.

Modifications may be resorted to within the spirit and scope of the appended claims.

I claim:

1. A loose cover for containers comprising a circular top provided with a central raised portion, the medial part of said raised portion being cut away to provide a central opening surrounded by a marginal inwardly extending rim, a hub-like enlargement including a dome-like top and a depending side wall, the lower edge of the side

wall being flanged over said inwardly extending rim, said side wall being substantially cylindrical and having its upper region flared outwardly to provide an internal annular channel in the enlargement, and a register for the lower end of the enlargement including a substantially circular disk having a series of axially extending divergent fingers formed thereon, said fingers having their medial portion disposed in frictional engagement with the medial portion of the side wall of the enlargement and having their extremities extending outwardly into said annular channel, and a rotary cut-off disk secured to said circular disk.

2. A loose cover for containers comprising a circular top provided with a central raised portion, the medial part of said raised portion being cut away to provide a central opening surrounded

by a marginal inwardly extending rim, a hub-like enlargement including a dome-like top and a depending side wall, the lower edge of the side wall being flanged over said inwardly extending rim, said side wall being substantially cylindrical and having its upper region flared outwardly to provide an internal annular channel in the enlargement, and a register for the lower end of the enlargement including a substantially circular disk having a series of axially extending divergent fingers formed thereon, said fingers having their medial portion disposed in frictional engagement with the medial portion of the side wall of the enlargement and having their extremities extending outwardly into said annular channel, and a cut-off disk secured to said circular disk.

LOUIS HERMANI.
